US0D1048229S

(12) **United States Design Patent** (10) **Patent No.:** **US D1,048,229 S**
(45) **Date of Patent:** **** Oct. 22, 2024**

(54) **TOY PIECE**

(71) Applicant: **Idea Vault Holdings Inc**, Ashland, OR (US)

(72) Inventors: **Joshua J Gedlick**, Medford, OR (US); **Jordan M Willing**, Ashland, OR (US); **Howard Allen Wilson, IV**, Medford, OR (US)

(73) Assignee: **Idea Vault Holdings, Inc.**, Ashland, OR (US)

(**) Term: **15 Years**

(21) Appl. No.: **29/720,593**

(22) Filed: **Jan. 14, 2020**

(51) LOC (14) Cl. **21-01**

(52) U.S. Cl.

USPC **D21/484**; D21/561

(58) **Field of Classification Search**

USPC D21/483-484, 487-488, 495, 505, 561;

D23/250, 252, 253

CPC A63H 33/08; A63H 33/06

See application file for complete search history.

(57) **CLAIM**

The ornamental design for toy piece, as shown and described.

DESCRIPTION

FIG. 1 is a right elevation view of a toy piece; FIG. 2 is a front elevation view of the toy piece of FIG. 1; FIG. 3 is a left elevation view of the toy piece of FIG. 1; FIG. 4 is a rear elevation view of the toy piece of FIG. 1; FIG. 5 is a top elevation view of the toy piece of FIG. 1; FIG. 6 is a bottom elevation view of the toy piece of FIG. 1;

FIG. 7 is a top perspective view of the toy piece of FIG. 1; and,

FIG. 8 is a bottom perspective view of the toy piece of FIG. 1.

The broken line showing of the toy piece is for the purpose of illustrating portions of the article that forms no part of the claimed design.

The broken lines and colors are shown for illustrative purposes only and form no part of the claimed design.

1 Claim, 8 Drawing Sheets
